UNITED STATES PATENT OFFICE.

CHARLES J. HOLUB, OF NEWPORT, KENTUCKY, ASSIGNOR TO THE WILLIAMSON HEATER COMPANY, OF CINCINNATI, OHIO, A CORPORATION OF OHIO.

HOT-AIR-CONDUCTOR PIPE.

1,122,392.

Specification of Letters Patent. Patented Dec. 29, 1914.

Application filed February 2, 1914. Serial No. 815,897.

To all whom it may concern:

Be it known that I, CHARLES J. HOLUB, a citizen of the United States, and residing at Newport, in the county of Kenton and 5 State of Kentucky, have invented a new and Improved Hot-Air-Conductor Pipe, of which the following specification is a full disclosure.

This invention relates to an improvement 10 in sectional pipes, and primarily to that class known as hot-air conductor pipes used in connection with furnaces for heating purposes.

The object of this invention is to provide 15 means for locking two sections of pipe together at their meeting or telescoping ends.

Another object is to provide a snap-lock 20 for sectional hot-air furnace pipes stamped from the body portion of the pipe and so formed that an ordinary wire nail may be used as a locking or binding medium.

Other novel features of construction and arrangement of parts are made apparent by the accompanying drawings, which, while 25 illustrating a preferred form of embodiment of this invention, are only intended to present to those skilled in this art the underlying principles thereof, that they may employ them in the numerous modifications 30 contemplated within their scope. These drawings have been annexed as a part of this disclosure, like characters of reference denoting corresponding parts throughout the several figures of which:—

35 Figure 1 is a perspective view of the lower end of a pipe length showing one of the locking elements. Fig. 2 is a perspective view of the upper end of a companion pipe section showing a second locking element 40 adapted to register with that shown in Fig. 1. Fig. 3 is a fragmentary perspective view of both sections showing the locking elements intermeshed and the locking member in engagement therewith. Fig. 4 45 is a detailed section through the marginal ends of the jointed ends of the sections and locking elements.

Continuing now to describe the illustrated 50 adaptation of this invention, it will be preliminarily stated that while I have shown rectangular hot-air conductor piping of double wall formation, of a type having an intermediate air space, it is obvious that my

improvement is equally adaptable to a single walled pipe of any contour.

A, B, represent pipe sections or lengths 55 having their end arranged to be telescopically intermeshed, with each section formed of inner and outer walls 1, 2, respectively, inclosing an intermediate air space. The 60 walls 1, 2, of each section are united at their ends; at one end the outer wall 2 tapering toward the inner wall 1, and at the other end the inner wall 1 tapering toward the outer wall 2. Near the lower edge of the 65 pipe section A, (see Fig. 1), is formed an aperture 3, said section having countersunk surfaces forming opposing tapered recesses 4 at either side thereof. Near the top of the pipe section B, (see Fig. 2) at a position 70 adapted to register with the aperture 3 of the section A, when said sections are intermeshed, is a hollow bead or eye 5, punched outwardly from the side wall 2, said wall at either side of said eye having counter- 75 sunk recesses 6 similar in form to and adapted (when these sections are intermeshed) to register with, the recesses 4 of the companion section.

When two sections of pipe are united (see 80 Fig. 3) the eye 5 of one section projects through the aperture 3 of the companion section. During this uniting of the sections the lower edge of the section A will, by reason of the natural spring of the metal 85 snap over the eye 5, constituting what may be termed a snap-lock, needing only a binding or locking member to make a positive lock. To lock the sections together I forcibly thread an ordinary wire nail 7 beneath 90 the eye 5, leaving the ends projecting on either side thereof and frictionally bearing against the side wall. The crown of the eye 5 is approximately in the same plane as the outer surface of the side wall, the counter- 95 sunk tapered recesses permitting the threading of the nail beneath the eye 5 and the natural spring of the nail or tie rod 7 providing frictional resistance against withdrawal. It is obvious that a piece of spring 100 wire or rod may be substituted for the nail, therefore I do not wish to limit myself to the use of a nail as a binding element.

The countersunk surfaces of the aper- 105 tured or outer section adjacent the open ends of the projecting eye, constitute guides

for the tie rod, enabling its ready insertion through the eye, and also serve so to limit the projection of the locking elements that they lie approximately flush with the plane 5 surface of the outer pipe section.

Having described my invention, I claim:—

1. A device of the class described, combining two sheet metal pipe sections to be telescopically united in a tight fitting joint, 10 the margin of the inner fitting section being formed with a struck-up eye and countersunk adjacent the edges of said eye, the corresponding margin of the other section being apertured and correspondingly countersunk, said margins being relatively 15 resilient enabling the eye to snap through said aperture when the section ends are appropriately telescoped.

2. A device of the class described, combining two sheet metal sections telescopically united in a tight fitting joint, the margin of the inner fitting section being formed with a struck-up eye and countersunk adjacent the ends of said eye, the corresponding 25 margin of the other section being apertured and correspondingly countersunk with said eye projecting outwardly through the same and a tie inserted through said eye and held in wedging engagement relative to said 30 countersunk surface.

3. A device of the class described, combining two sheet metal pipe sections to be telescopically united in a tight fitting joint, the margin of the inner fitting section being formed with a struck-up eye extending parallel with the joint, the metal surface adjacent the open ends of the eye being countersunk, the corresponding margin of the outer section being apertured, and correspondingly countersunk, and a tie inserted 40 through the projecting portion of said eye and held in wedging engagement relative to said outer countersunk surface.

4. A device of the class described combining two sheet metal pipe sections telescopically united in a tight fitting joint, the overlapping joint margins being formed respectively with an interlocking aperture and eye and countersunk adjacent the aperture 45 and the open ends of the eye and a tie inserted through the eye and retained in wedging relation with the margin surface.

5. A sectional conductor pipe, comprising two sections having an aperture at one marginal end of each section and provided with 55 countersunk surfaces, an eye stamped out-

wardly from the body portion of the opposite marginal end of each section adapted to intermesh with the aperture of an adjacent section when the sections are telescopically 60 united and an independent locking tie rod adapted to be threaded beneath the eye to lock the sections together.

6. A sectional conductor pipe, comprising two sections having an aperture at one marginal end of each section, an eye stamped outwardly from the body portion of the opposite marginal end of each section, adapted to intermesh with the aperture of an adjacent section when the sections are 70 united, said eye being approximately in the same plane as the outer surface of the apertured end, the apertured end being provided with countersunk opposing recesses 75 adjacent the aperture, and a tie rod adapted to be threaded through said eye and frictionally held in locking position.

7. A sectional conductor pipe, comprising two sections having an aperture at one marginal end of each section, an eye stamped outwardly from the body portion of the opposite marginal end of each section adapted to intermesh with the aperture of an adjacent section when the sections are united, a tie rod for the eye, the crown of said eye 80 extending beyond the outer surface of the apertured end a distance, less than the thickness of the tie rod, said apertured end being provided with countersunk recesses adjacent the aperture permitting the tie rod 85 to be threaded through said eye to and frictionally held in locking position.

8. A device of the nature disclosed comprising two sheet metal pipe sections to be telescopically united in a tight fitting joint, 90 the margin of the inner fitting section being formed with a struck-up eye and the corresponding margin of the outer fitting section being apertured, the marginal surface adjacent said struck-up eye being 95 shaped to enable the insertion of a tie rod through the eye and to hold the rod in wedging engagement relative to the eye and the apertured section.

In witness whereof, I hereunto subscribe my name, as attested by the two subscribing witnesses.

CHARLES J. HOLUB.
